DESIGN FOR A DISPLAY BOX

Jack G. Allen, Chicago, Ill., assignor to F. H. Noble & Co., Chicago, Ill., a corporation of Illinois

Application August 12, 1938, Serial No. 79,299

Term of patent 7 years

To all whom it may concern:

Be it known that I, Jack G. Allen, a citizen of the United States, residing at Chicago, in the county of Cook, State of Illinois, have invented a new, original, and ornamental Design for a Display Box, of which the following is a specification, reference being had to the accompanying drawing, forming a part thereof.

In the drawing:

Fig. 1 is a perspective view of a display box showing my new design;

Fig. 2 is a top plan view of said box; and

Figs. 3 and 4 are respectively front and end elevations of the same.

I claim:

The ornamental design for a display box, as shown.

JACK G. ALLEN.
